UNITED STATES PATENT OFFICE.

WILLIAM M. WHITE, OF MILWAUKEE, WISCONSIN.

HYDRAULIC NOZZLE.

1,187,588.

Specification of Letters Patent. Patented June 20, 1916.

Application filed March 12, 1913. Serial No. 754,124.

To all whom it may concern:

Be it known that I, WILLIAM M. WHITE, a citizen of the United States, residing at Milwaukee, in the county of Milwaukee and State of Wisconsin, have invented a certain new and useful Improvement in Hydraulic Nozzles, of which the following is a specification.

This invention relates to improvements in the construction of hydraulic nozzles such as are universally employed in hydraulic power plants, mining and analogous arts.

An object of the invention is to provide a hydraulic nozzle which is simple in construction and efficient in operation and in which the means for changing the direction and the size of the jet are confined within a stationary nozzle casing.

Another object of the invention is to provide means for balancing the pressures on movable parts within the nozzle and especially the pressure acting in line with the casing openings and parallel thereto, thereby reducing to a minimum the wear and the power required to shift the movable parts.

Still another object of the invention is to provide connections operable through one of a pair of aligned openings in the casing, for manipulating the jet discharged from the nozzle through one of the openings.

Some of the primary features of the nozzle disclosed in this application are claimed broadly in application Serial No. 700,541, filed May 27, 1912.

A clear conception of several embodiments of the invention may be had by referring to the drawing accompanying and forming a part of this specification in which like reference characters designate the same or similar parts in the various views.

Figure 1 is a central vertical section through a nozzle and a portion of the supply pipe leading thereto. Fig. 2 is a transverse vertical section through the nozzle disclosed in Fig. 1, the section being taken along the line II—II of Fig. 1 looking in the direction of the arrow. Fig. 3 is a central vertical section through a modified form of nozzle and a portion of the supply pipe leading thereto. Fig. 4 is a transverse vertical section through the nozzle disclosed in Fig. 3, the section being taken along the line IV—IV of Fig. 3 looking in the direction of the arrow. Fig. 5 is a central vertical sec-

tion through a modified form of nozzle and a portion of the supply pipe leading thereto. Fig. 6 is a transverse vertical section through the nozzle disclosed in Fig. 5, the section being taken along the line VI—VI of Fig. 5 looking in the direction of the arrow.

Referring to Figs. 1 and 2, the stationary nozzle casing consists essentially of a body portion 4, a front cap 19 and a rear cap 18. The front and rear caps 19, 18, are provided with aligned front and rear casing openings respectively, which are substantially equal in cross-sectional area, and through the former of which the jet discharged from the nozzle is projected. The fluid supply pipe 8, which normally contains fluid, usually water, under pressure, connects with the body portion 4 of the nozzle casing. The upper half of the body portion 4 is preferably formed as a removable cap whereby ready access to the interior of the casing is permitted for purposes of inspection and removal of the parts.

The movable means within the stationary nozzle casing comprises a jet direction-changing or deflecting hood 2 supported in bearings in the casing wall by means of pins 3 which project horizontally from the mid portion of the hood 2. The front cap 20 of the hood 2 is provided with a suitably directed orifice which connects with the front casing opening and through which the jet leaving the nozzle is projected. The fluid from the supply pipe 8 enters the interior of the hood 2 through a suitably directed passage leading into the hood 2 adjacent the supply pipe 8. A means for controlling the size or cross-section of the jet delivered from the nozzle is provided in the form of an adjustable needle 1 which is movable within the jet orifice and the movement of which varies the effective area of the jet orifice.

The cap 20 of the hood 2 is provided with a curved surface 9 generated about the common axis of the pins 3 as a center line. The surface 9 of the cap 20 coacts with a similarly formed surface of the casing cap 19, the joint between the coacting caps 19, 20, being packed by means of a suitable packing 11. The flange 42 at the rear end of the hood 2 is provided with a curved surface 10 also generated about the common axis of

the pins 3 as a center line. The surface 10 of the flange 42 coacts with a similarly formed surface of the casing cap 18, the joint between the coacting elements being 5 packed by a suitable packing 12. The surfaces 9, 10, of the hood 2 as disclosed, are preferably spherical or cylindrical in form but the invention is not limited to surfaces generated on a finite radius. It should be 10 noted that the essential form of the hood 2 comprises only front and rear portions connected rigidly together, these portions having surfaces coacting respectively with the front and rear openings in the casing. The 15 interior of the stationary nozzle casing is constantly in communication with pressure from the supply pipe 8; thus permitting pressure to act upon the inner surfaces of the packings 11, 12, to hold them firmly in 20 place.

The rearwardly extending sleeve 71 formed on the hood 2 passes through the rear casing opening and provides a suitable bearing for the stem of the needle 1. At 25 the point of emerging of the needle stem from within the sleeve 71, a suitable stuffing box 13 is provided. The collar 7 is adjustably secured to the sleeve 71 and has horizontally projecting pins 6 which are connected with a suitable jet deflecting mechanism by means of the connecting rods 5. The jet deflecting mechanism for actuating the hood 2 through the connections, comprising the rod 5, collar 7 and sleeve 71, 30 may be of any of the well known forms, one of which is illustrated in my prior application above referred to. The yoke 14 is supported directly upon the sleeve 71 and has an end hub within which the screw-threaded bushing 15 is journaled. The hand-wheel 17 is clamped to the bushing 15 by means of a locking nut 16. The hand-wheel 17, nut 16 and bushing 15 are rotatable as a unit 35 within the hub of the yoke 14, but are locked against longitudinal movement relative to the yoke 14. The screw-threaded end of the stem of the needle 1 coacts with the screw-threaded interior of the bushing 15 so that upon rotation of the hand-wheel 17, the 40 needle 1 is shifted longitudinally within the jet orifice.

In the modified form of nozzle disclosed in Figs. 3 and 4, the stationary nozzle casing consists essentially of a body portion 24 and a front cap 219. The front cap 219 and the rear end of the portion 24 of the casing are provided with aligned front and rear openings respectively which are of substantially equal cross-sectional area. As disclosed, the rear casing opening is circular having a diameter substantially equal to that of a spherical member 210, while the front casing opening is elliptical in form, having a width somewhat greater than the maximum diameter of the jet, and having a

length sufficiently great to permit the desired jet deflection. The fluid supply pipe 28 connects with and conducts fluid into the interior of the casing portion 24. Access to the interior of the stationary casing is 70 permitted by removal of the cap 219.

The movable hood 22 is shiftably mounted within a stationary casing by means of the spherical member 210 supported in a bearing 218 formed in the casing portion 24. 75 The front cap 230 of the hood 22 is provided with a suitably directed orifice which connects with the front casing opening and through which the jet projected from the nozzle passes. The fluid from the supply pipe 28 enters the hood 22 through a suitable opening in the lower side thereof. The adjustable needle 21 which is movable longitudinally within the hood orifice, controls the effective area of the passage through the 80 jet orifice.

The cap 230 of the hood 22 is provided with a curved surface 29 generated about the axis of swing of the hood 22 as a center line. The adjacent surfaces of the cap 219 are similarly formed and coact with the surface 29 of the cap 230. The joint at the coaction of the caps 219, 230 is packed by means of suitable packing 211. The sleeve 72 formed on the hood 22 passes through the spherical member 210 and provides a bearing for the stem of the needle 21. The stuffing box 213 prevents leakage from within the casing to the atmosphere past the needle stem. The yoke 27 is rigidly secured to the sleeve 72 and has two forwardly projecting arms which take over the bearing pins 23. The yoke 27 clamps the spherical member 210 against a shoulder on the hood 22. The common axis of the pins 23 passes through the center of the spherical member 210 and prevents shifting of the hood 22 in any plane other than a vertical plane. 95

The yoke 214 is secured to the sleeve 72 and has an end hub within which the screw-threaded bushing 215 is journaled. The jet deflecting mechanism connects with pins 26 formed on the yoke hub by means of suitable connections 25. The hand-wheel 217 is clamped to the bushing 215 by means of a lock nut 216. The hand-wheel 217, nut 216 and bushing 215 are rotatable as a unit within the hub of the yoke 214 but are locked against longitudinal movement relative to the yoke 214. The end of the stem of the needle 21 has screw-thread connection with the bushing 215 so that rotation of the hand-wheel 217 will shift the needle longitudinally to vary the effective area of the jet orifice. 100

In the modified form of nozzle disclosed in Figs. 5 and 6, the stationary nozzle casing consists essentially of a body portion 34 and a front cap 319. The cap 319 and rear end of the portion 34 are provided with 110

aligned front and rear casing openings respectively which are of substantially equal cross-sectional area. The fluid supply pipe 38 connects with and conducts fluid into the 5 casing portion 34. Accessibility to the interior of the stationary casing is permitted by removal of the cap 319 which, as disclosed, is formed in two parts.

The movable hood is shiftably mounted 10 within the stationary casing by means of pins 33 which project horizontally from the front portion 320 of the hood 32 and are journaled within the cap 319. The jet orifice formed in the front portion 320 of the 15 hood 32, forms a discharge passage from within the nozzle continuous with the front casing opening. The fluid from the supply pipe 38 enters the hood 32 through a suitable opening at the bottom thereof. The 20 adjustable needle 31 is movable longitudinally within the jet orifice and controls the effective area of the orifice.

The front end portion 320 of the hood 32 is provided with curved surfaces 39 generated about the common axis of the pins 33 as a center line. The adjacent surfaces of the cap 319 are similarly formed to coact with the surfaces 39 of the hood 32. The joint at the coaction of the cap 319 with 25 the hood 32 is suitably packed by means of packing 311. The flange 342 at the rear end of the hood 32 is provided with a curved surface 310, also generated about the common axis of the pins 33 as a center line. 30 The surface 310 of the flange 342 coacts with a similarly formed surface of the casing portion 34, the joint at the coaction of these surfaces being provided with suitable packing 312. The interior surfaces of the 35 packings 311, 312, are constantly in communication with pressure from the supply pipe 38.

The rearwardly projecting sleeve 73 formed on the hood 32 passes through the 40 rear casing opening and provides a suitable bearing for the stem of the needle 31. The joint between the sleeve 73 and the needle stem is packed by means of a stuffing box 313. The collar 37 is adjustably secured to 45 the sleeve 73 and has horizontally projecting pins 36 connected with a suitable deflecting mechanism by means of connecting rods 35. The yoke 314 is mounted on the sleeve 73 and has an end hub within which the 50 screw-threaded bushing 315 is journaled. The hand-wheel 317 is clamped to the bushing 315 by means of the lock nut 316. The hand-wheel 317, lock nut 316 and bushing 315 are rotatable as a unit within the yoke 55 hub and are locked against longitudinal movement relative to the yoke 314. The bushing 315 has a screw-thread coaction with the stem of the needle 31 so that rotation of the hand-wheel shifts the needle to 60 vary the effective jet orifice.

During the operation of the nozzle, if it is desired to vary the size or cross-sectional area of the jet, this may be done by turning the hand-wheel 17, 217, 317, in the proper direction, thus shifting the needle 1, 21, 31, 70 longitudinally within the jet orifice. By bringing the needle 1, 21, 31, forward until the needle bulb coacts with the edges of the jet orifice, the jet may be cut off entirely. If it is desired to change the direction of 75 the jet, this may be done by raising or lowering the connection 5, 25, 35, thereby causing the hood 2, 22, 32, to swing about the axis of the pins 3, 23, 33, and causing the needle 1, 21, 31, to assume a new angular position. 80

For convenience of illustration, the pivot pins 3, 23, 33, have been disclosed as actual pivots positioned within the limits of the stationary nozzle casing, but it is not intended to confine the scope of this invention 85 to the location of these pivots within definite limits. The connections for shifting the movable means to change the direction of the jet, have also been disclosed as operable through only one of the casing openings 90 and specifically through the rear casing opening, such disclosure having been selected merely as one of the specific forms of embodiment of the invention.

If the casing 4 were entirely inclosed, all 95 elements located within it would be completely pressure balanced, except for the buoyant force acting thereon. In order to permit discharge of the jet from the casing, it is necessary to provide the front casing 100 opening. In order to permit variation in the direction and size of the jet, it is necessary to provide as elements inclosed within the casing 4, the deflectable hood and the needle for controlling the jet orifice of the 105 hood. By bringing the hood with its jet orifice closed, into engagement with the casing so as to cover the front opening, the pressure acting upon the surfaces of the 110 hood which are in line with the front casing opening, would force the hood forwardly in line with the openings. If with the elements thus formed and positioned, the needle were opened to normal operating position, a jet would be delivered from the jet orifice, and the forward pressure upon the hood would 115 be decreased by an amount approximately equal to unit supply pressure times the cross-sectional area of the jet orifice. This would leave the hood still subjected to a forward 120 pressure equal to the pressure acting upon an area equal to the casing opening less the pressure acting upon an area equal to the cross-section of the jet.

In order to counterbalance this forward 125 pressure upon the hood, the rear casing opening is provided, which is closed by an extension of the hood. The rear casing opening is formed of such size that the rearward pressures acting upon the surfaces of the 130

hood and in line with the casing openings, exactly balance the unbalanced forward pressure upon the hood.

As the area of cross-section of the jet is relatively small, the front and rear casing openings may be defined as being substantially equal. As the pressures acting upon the nozzle hood in directions transverse to the line of the casing openings are automatically balanced, the only pressures which are balanced by the formation of the front and rear openings of proper relative size, are the components of pressures acting upon such surfaces of the hood which are transverse to and in line with the casing openings. This complete balancing of the pressures upon the hood permits shifting of the hood with the expenditure of minimum power and also eliminates undesirable shifting of the hood due to unbalanced pressure acting thereon.

It should be understood that it is not desired to be limited to the exact details of construction shown and described, for obvious modifications will occur to a person skilled in the art.

It is claimed and desired to secure by Letters Patent,—

1. In a nozzle, a stationary casing having front and rear aligned openings, a fluid supply pipe connected to said casing, movable means within said casing, means for controlling the size of the jet discharged from said casing through said front opening, and connections operable through one of said openings to shift said movable means whereby the direction of the jet is changed.

2. In a nozzle, a stationary casing having front and rear aligned openings, a fluid supply pipe connected to said casing, movable means within said casing and having a passage formed therethrough continuous with said front opening, means for controlling the size of said passage, and connections operable through one of said openings to shift said movable means whereby the direction of the jet discharged from said passage is changed.

3. In a nozzle, a casing having front and rear aligned openings, a supply pipe connected to said casing, means within said casing for changing the direction of the jet discharged from said casing through said front opening, and connections operable through one of said openings to shift said jet direction-changing means.

4. In a nozzle, a casing having front and rear aligned openings, a supply pipe connected to said casing at a point intermediate said openings, means within said casing for changing the direction of the jet discharged from said casing through said front opening, means within said casing for control-

ling the size of the jet, and connections operable through one of said openings for actuating said jet size-changing means.

5. In a nozzle, a casing having front and rear aligned openings, means for supplying fluid under pressure to said casing, means within said casing for changing both the direction and size of the jet discharged from said casing, through said front opening, and connections operable through one of said openings to actuate said jet-direction- and size changing means.

6. In a nozzle, a casing having a discharge opening, a supply pipe communicating with the interior of said casing, and means for changing the direction of the jet discharged from said casing, said means having its opposite ends formed to effect balancing of pressures acting on said means in line with said discharge opening.

7. In a nozzle, a casing having front and rear aligned openings, a supply pipe connected to said casing, means for changing the direction of the jet leaving said casing through said front opening, and means cooperating with said rear opening and providing a counterbalancing pressure on said jet-direction-changing means in line with said casing openings.

8. In a nozzle, a casing having front and rear aligned openings, a supply pipe connected to said casing, a hood for changing the direction of the jet leaving said casing through said front opening, connections operable through one of said openings for moving said hood, and means for substantially balancing the pressures on opposite ends of said hood.

9. In a nozzle, a casing having a front opening for discharge of a jet, and a jet-direction-changing means within said casing, said casing having a rear opening for coaction with said means, for permitting manipulation of said means and for balancing same in line with said casing openings.

10. In a nozzle, a casing having front and rear openings of substantially equal cross-sectional area, and pressure balanced jet-direction-changing means within said casing extending between said openings.

11. In a nozzle, a casing having front and rear aligned openings of substantially equal cross-sectional area, and pressure balanced jet-direction-changing means within said casing movable transversely to the line of said openings.

In testimony whereof, the signature of the inventor is affixed hereto in the presence of two witnesses.

WITNESS: WILLIAM M. WHITE.
